CLAIM

The ornamental design for an inventor's recognition plate, as shown and described.

DESCRIPTION

FIG. 1 is a front elevational view of an inventor's recognition plate showing my new design, the back being identical;

FIG. 2 is a left side elevational view thereof;

FIG. 3 is a right side elevational view thereof;

FIG. 4 is a top plan view thereof; and

FIG. 5 is a bottom plan view thereof.
